Primary Examiner — Kevin K Rudzinski*Assistant Examiner* — Elizabeth Anne Glassberg(74) *Attorney, Agent, or Firm* — Nitin Kaushik(57) **CLAIM**

The ornamental design for a beehive stand, as shown and described.

DESCRIPTION

FIG. 1 is a front perspective view of a beehive stand, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and, FIG. 10 is a second rear perspective of the beehive stand of FIG. 1, shown in an alternate configuration.

The broken lines in the drawings illustrate the portions of the beehive stand, which form no part of the claimed design. The dash-dot-dash broken lines FIGS. 1 and 9 show the boundaries of the enlarged portion of FIG. 1 and form no part of the claimed design.
